UNITED STATES PATENT OFFICE

147,342

DESIGN FOR A TABLECLOTH OR SIMILAR ARTICLE

John S. Madsen, New York, N. Y.

Application June 20, 1946, Serial No. 130,880

Term of patent 3½ years

(Cl. D92—26)

To all whom it may concern:

Be it known that I, John S. Madsen, a citizen of the United States of America, residing in New York city, county of New York, and State of New York, have invented a new, original, and ornamental Design for a Tablecloth or Similar Article, of which the following is a specification, reference being had to the accompanying drawing, forming part thereof.

The figure on the drawing shows one-half of a tablecloth or similar article showing my new design, the other half being identical therewith arranged in proper relation to complete the cloth.

The design is repeated to the right on the drawing.

I claim:

The ornamental design for a tablecloth or similar article, substantially as shown and described.

JOHN S. MADSEN.
